INVENTOR,

HUGO LENTZ,
BY *Frank D. Dernoncourt*
HIS ATTORNEY.

UNITED STATES PATENT OFFICE.

HUGO LENTZ, OF BERLIN, GERMANY.

TURBINE-WHEEL HAVING REMOVABLE PADDLES.

No. 802,459.

Specification of Letters Patent.

Patented Oct. 24, 1905.

Application filed May 26, 1905. Serial No. 262,492.

To all whom it may concern:

Be it known that I, HUGO LENTZ, a subject of the German Emperor, residing at Berlin, Germany, have invented a new and useful 5 Turbine-Wheel Having Removable Paddles; and I do hereby declare the following to be a full, clear, and exact description of the same.

This invention relates to a form of turbine-wheel having removable paddles and to a 10 method for easily and securely attaching paddles to turbine-wheels.

The object of my invention is to produce a turbine-wheel having the paddles, while readily removable, securely locked thereto.

15 In the accompanying drawings I have shown embodiments of my invention.

Figure 1 is a cross-sectional view of a portion of a turbine-wheel, showing the paddles assembled in place. Fig. 2 is a side view of 20 a portion of a wheel, the paddles not being attached; and Fig. 3 is a longitudinal section of said wheel.

The wheel may have peripheral projecting 25 paddle-supports, which may be bars or rods *b*, preferably affixed to or integral with the wheel-rim, and these bars or rods may be square or have projecting edges or be grooved or ribbed or otherwise formed to prevent the turning thereon of the attached paddles.

30 The turbine-wheel shown in my drawings is provided with a grid or grate like periphery comprising the bars *b* and a continuous peripheral rim and having the openings *d*. The body of the wheel is indicated at *e*. The said 35 paddles *a* may have the usual or any desired curved impact-faces and be formed or provided with any suitable means for engaging directly or indirectly with the rods or bars *b*. If desired, the paddles may have rearwardly-

40 projecting wings, as shown in Fig. 1, thus forming a recess in the rear of the blade reversely corresponding to the exterior of a rod

or bar *b*. By this means a tight fit between the paddle and supporting rod or bar is assured; but an additional pin, bar, rod, or key 45 may be used to assure a tight engagement of the parts.

In fitting the form of paddles shown in Fig. 1 the paddle will be first slid into place and the rear edges of the wings will be bent toward one another to form the locking-flanges 50 *c*. If desired, such locking-flanges may be formed upon the wings before attachment to the wheel.

In place of the flanges *c* any other form of 55 locking connection, either integral with or separate from the paddles, may be used.

My present invention will be found useful either with axial or radial turbines.

What I claim, and desire to secure by Letters Patent, is—

1. A turbine-wheel having peripherally-projecting paddle-supports and a continuous wheel-rim integral with and at the outer ends of said supports. 65

2. A turbine-wheel having peripherally-projecting paddle-supports, and a continuous wheel-rim integral with and at the outer ends of said supports, and removable impact-paddles rigidly secured into engagement with the 70 paddle-supports.

3. A turbine-wheel having peripherally-projecting paddle-supports, a continuous wheel-rim integral with and at the outer ends of said supports, and removable impact-paddles having rearwardly-projecting wings, 75 which slidably engage the paddle-supports.

In testimony whereof I have signed my name to this specification in the presence of two subscribing witnesses.

HUGO LENTZ.
